EXPANSIBLE LINK OR ADJUSTMENT MEMBER FOR BRACELETS, WRISTBANDS, WRIST WATCHES, AND THE LIKE

Seymour Steinberg, Philadelphia, Pa.

Application February 1, 1935, Serial No. 4,453

2 Claims. (Cl. 24—68)

The present invention relates to an adjustment link for bracelets and more particularly wrist watch bracelets or wrist watch straps, whereby the circumferential dimension of the wrist watch, 5 (the watch and bracelet, or the watch and wristband combined) may be increased and decreased at will, so as to permit the hand to be slipped through and then to permit the circumferential dimension to be decreased to the wrist dimension.

10 A further object of the present invention is to provide a device of this character which will be durable, effective and dependable in use.

With the above and other objects in view, which will appear from the following detailed description, the present invention consists of two telescopically arranged members adapted to be disposed in slidable relation to each other, a spring tending at all times to move the two telescopically related members with respect to each other, 20 so as to extend their overall dimension in the direction of the circumference of the wrist band or bracelet (of which the device is intended to form a part or a link), and a toothed rack carried by one of said members, and a spring-pressed 25 pawl or detent carried by the other of said members, arranged to coact with each other so as to retain the two telescopically related members in any desired position with respect to each other (within the limits of adjustment) against the 30 force of the spring, and manually operable means whereby the pawl or detent member may be disengaged from the toothed rack at will.

The present invention further consists of other novel features and details of construction, all of 35 which will appear more fully from the following description.

For the purpose of illustrating the invention, there is shown in the accompanying drawings a form thereof which is at present preferred, although it is to be understood that the various instrumentalities of which the invention consists can be variously arranged and organized and that the invention is not limited to the precise arrangement and organization of the instrumentalities as herein shown and described.

40 Referring to the drawings, in which like reference characters indicate like parts:

Figure 1 represents a rear view of the device embodying the present invention, shown partly 45 broken away, and showing the collapsed or contracted position;

Figure 2 represents a similar view shown in an expanded or in an extended position;

Figure 3 represents a side elevational view of 50 the device in the extended position;

Figure 4 represents a section on line 4—4 of Figure 2;

Figure 5 represents a perspective view of the outer telescopic member;

Figure 6 represents a perspective view of the 5 inner telescopic member, and

Figure 7 represents a perspective view of the detent spring.

According to the present invention, outer and inner telescopic members 8 and 9 are provided, 10 and formed preferably of sheet metal. The outer member 8 is composed of the main body panel 10, slightly curved in a longitudinal direction, so as more or less to conform to the general curvature of the wrist, and along one of the longitudinal edges thereof the right-angular flange 11 is formed, and the over-hanging flange 12 is formed in continuation thereof, and generally parallel to the body panel 10, so as to form a parallel channel-like space serving as one of the two guides for 20 the inner telescopic member.

Along the opposite longitudinal edge a similar upright flange 13 is formed from which the over-hanging flange 14 extends in direct continuation thereof, and from which the flange 15 extends 25 downwardly towards the body panel 10, thereby forming a more or less closed channel or tube, serving as the other guide for the inner telescopic member 9. The flange portion 15 does not extend quite to the body panel 10, but extends to 30 within a short distance of it and more particularly a distance approximately the same as the thickness of the body panel 16 of the inner telescopic member 9.

The inner telescope member 9 is similarly 35 curved, as indicated particularly in Figures 3, 5 and 6, and is provided along one of its longitudinal edges with the upright flange 17 and the over-hanging flange or rack portion 18, having teeth 19 formed in its edge, inclined in saw-fashion in 40 one direction. A longitudinal slot 20 is formed in the flange portion 17 for a substantial part of its length. Along the opposite longitudinal edge of the body panel 16 another flange 21 is formed.

The tubular portion along one of the longitudinal edges of the outer member 8 is closed by an end wall 22 which serves as a spring abutment and which may be formed of the flange 13 and bent over, while a corresponding spring abutment 23 is formed on the member 9 by pressing up a 50 small part of the body panel 16, as shown at 23.

The opposite ends of the members 8 and 9 may be provided with suitable linking or connecting means, such as tubular formations 24 and 25, rolled up out of the body panels, which may serve 55

to receive pivot pins or pintles, or hinges of any suitable bracelet, wrist strap, or other devices, as for instance the pivots or pintles 26 and 27 of the bracelet links 28 and 29.

5 The member 9 is telescoped within the member 8, as indicated in Figures 1, 2, 3, and 4, with a compression spring 30 interposed between the spring abutment 22 and the spring abutment 23, thereby tending to extend or expand the two members with respect to each other, as indicated 10 particularly in Figure 2.

A generally U-shaped retainer spring member 31 is formed of generally flat metal, and is interposed between the two telescopic members in a manner shown particularly in Figures 1, 2, and 4. 15 The thickness of the sheet metal of which the spring 31 is formed is slightly greater than the gap between the flange 15 and the body panel 10, and a pair of somewhat thinner anchorage 20 members 32 and 33 are provided, projecting therefrom, which are thin enough to extend between the portions 15 and 10 of the outer telescopic member 8, as indicated particularly in Figures 1 and 4.

25 The other side of the U-shaped spring is provided with an anchorage toe 34, and a finger piece or knob 35, and a detent or pawl 36. The anchorage toe 34 projects through a suitable opening 37 in the side flange 11, while the finger piece 35 extends through the slot 20 and then through another opening 38 in the side flange 11, whereby it may be depressed from without with the finger or with the nail of a finger, there being a slight recess or depression 39 provided in the 35 end of the knob for nail engagement. The pawl or detent 36 coats with the teeth 19 of the rack portion 18, and serves to interlock therewith in such a manner as to oppose the action of the spring 30.

40 Thus, to collapse or to contract the device, (and thus to contract the circumference of the wrist band or strap or bracelet) it is merely necessary to telescope the inner member further into the outer member and the pawl will lock the two members in their contracted position. When it 45 is desired to open the unit, it is merely necessary

to press in slightly on the knob 35, thereby to disengage the pawl or detent 36 from the toothed rack 18 and the spring 30 then automatically opens up the device to its outer limit of movement, which is determined by the end 40 of the slot 20, which engages the knob 35 at its outermost position.

5 The invention may be embodied in other specific forms without departing from the spirit or essential attributes thereof, and it is therefore desired that the present embodiment be considered in all respects as illustrative and not restrictive, reference being had to the appended claims rather than to the foregoing description to indicate the scope of the invention.

10 Having thus described the invention, what is hereby claimed as new and desired to be secured by Letters Patent, is:—

1. An expandible link or adjustment member for bracelets, wrist bands, wrist watches, and the like, comprising a pair of telescopically related members, slideable with respect to each other, a compression spring operatively interposed between said two members tending to distend the same relative to each other, and a manually operable spring- 20 pressed pawl operatively related to said two members, tending automatically to lock the same in any desired position against the force of the first-mentioned spring, and capable of being rendered inoperative by manual pressure from without. 25

2. An expandible link or adjustment member for bracelets, wrist bands, wrist watches, and the like, comprising a pair of telescopically related members, slideable with respect to each other, a compression spring operatively interposed between said two members tending to distend the same relative to each other, a toothed rack carried by one of said members, and a manually operable spring-pressed pawl carried by the other 40 of said members in operative alignment with said rack, tending automatically to lock the same in any desired position against the force of the first-mentioned spring, and capable of being rendered inoperative by manual pressure from without. 45

SEYMOUR STEINBERG.
